DICTATING MACHINE SWITCH

Theodore H. Beard and John E. Renholdt,
Bridgeport, Conn., assignors to Dictaphone Corporation, New York, N. Y., a corporation of New York

Original application June 24, 1933, Serial No. 677,447, now Patent No. 2,071,278. Divided and this application January 16, 1937, Serial No. 120,924

2 Claims. (Cl. 200—52)

This invention relates to improvements in dictating machines and more particularly to the motor circuit control mechanism.

The present application is a division of application Serial No. 677,447, filed June 24, 1933, now Patent No. 2,071,278.

One of the objects is to provide a more convenient and efficient switch operating mechanism. Another object is to provide a simple and practical arrangement of such mechanism in relation to a dictating machine having the usually exposed operating parts covered by a hood. Other objects will be in part obvious and in part pointed out hereinafter.

15 The invention accordingly consists in the features of construction, combinations of elements, and arrangements of parts as will be exemplified in the structure to be hereinafter described and the scope of the application of which will be 20 indicated in the following claims.

In the accompanying drawings in which is shown one of the various possible embodiments of our invention:

Fig. 1 is a perspective view of a covered dictating machine embodying the present invention, viewed from the left-hand corner;

Fig. 2 is a left end elevation of the machine;

Fig. 3 is a sectional view of a portion of the left end of the box-like sub-base taken substantially on line 3—3 of Fig. 2 and showing the mouthpiece support and motor circuit switch, the operation of which it controls;

Fig. 4 is a sectional view taken on line 4—4 of Fig. 3;

35 Fig. 5 is a detail section taken on line 5—5 of Fig. 4; and

Fig. 6 is a perspective view showing the construction of a part of the switch operating mechanism.

40 Similar reference characters refer to similar parts throughout the various views of the drawings.

Referring to the drawings, a dictating machine is shown comprising a base plate 12 hinged upon 45 and supported by a box-like sub-base 5 adapted to enclose certain parts of the machine, some of which may be supported upon the box itself while others depend from the under side of the base plate. This is the usual construction of a 50 well known type of dictating machine.

Rising from the left end of the base plate 12 is a left-hand standard 13, and from the right end of the base plate rises a right-hand standard 14. A housing 15 formed on the left end of 55 the base plate adjacent the standard 13 provides

a suitable bearing for a mandrel shaft 16 which supports a mandrel 17 at its right or outer end. Upon this mandrel a record cylinder may be mounted. A sound-box carriage 21 is mounted for travel longitudinally of the mandrel upon carriage rods, not shown, but which are supported at their ends in the standards 13 and 14.

Extending forwardly from the carriage 21 is the usual speaking tube 57 having at its outer end a mouthpiece and handle 56.

As is usual with dictating machines of the type described, as a preliminary to setting the machine in operation for recording or reproducing dictation it is customary for the operator to remove the mouthpiece from its hook. It has been 15 customary, too, in machines of this type, pivotally to mount the hook upon the left-hand standard of the machine, letting it project upwardly and forwardly to a position in front of and above the housing for the mandrel shaft. This hook 20 was then connected by means of suitable linkage with a switch in the motor circuit so arranged that when the mouthpiece was removed from the hook the switch in the motor circuit was closed, thus energizing the motor. Conversely, when 25 the mouthpiece was restored to the hook the motor circuit switch was opened and the machine brought to a standstill. While this mode of operation is very desirable, it has been found that the position of the hook as heretofore arranged is both awkward and unsightly.

A feature of importance of the present dictating machine is the provision of a novel mechanism for operating a switch in the motor circuit connected as heretofore with a support for the 35 mouthpiece of the speaking tube, but as shown herein it has been found possible and advisable to mount the mouthpiece support at the left end of the box-like sub-base of the machine, pivoting it so that it will lie in substantially a horizontal position for receiving the mouthpiece in a horizontal position instead of in the vertical position as heretofore. This new support is 40 advantageous in that it is easily accessible, does not obstruct the front of the machine, and its location is such that the mouthpiece is unlikely to be accidentally displaced from its support.

Referring to the drawings, it will be seen by reference to Figs. 3 and 4 that a bracket 105 is secured by means of bolts 106 to the inner surface of the left end 107 (as seen in Fig. 1) of the sub-base 5.

This bracket comprises an upper horizontal arm 108, a horizontal inwardly extending portion 109 and a downwardly extending portion 55

110. As shown herein the portion 110 of the bracket supports a switch 111 which need not be described further than to say that it is provided with a movable plunger portion 112 which in the 5 position shown in Fig. 3 provides for the engagement of cooperating electrical contacts within the switch so as to close-circuit the switch. This plunger is operated by means of a toggle lever comprising a pair of members 113 and 114. The 10 toggle lever 113 is pivotally mounted at 115 upon the arm 103 of the bracket. The lever 114 is pivotally mounted by means of a screw 116 on the lower end of lever 113, the screw passing through a slot 117 in said lever 114. This lever 15 114 also has a pin-and-slot connection with the plunger 112. At its upper end the lever 114 is provided with an angular cam surface 118 having a high point between its angulated sides. This cam surface engages a cam roller 119 rotatably supported upon the lever 113.
10. A tension spring 120 extends between a lug 121 on lever 113 and a lug 122 on lever 114. Should lever 113 be swung from the position shown in Fig. 3 about its pivot in a counter-clockwise direction, the roller 119 would ride up the side of the cam 118 with which it is shown in contact, depressing the lever 114 against the tension of the spring 120. After the roller 119 has passed the high point of the cam the spring will cause it rapidly to ride down the opposing cam surface. This will cause the toggle levers to pass from a straight line position to an angulated position opposite to that disclosed in Fig. 4. Such action will very rapidly snap the switch plunger outwardly from the position occupied by it in Fig. 3, thus providing a very quick break of the contact points within.
15. The lever 113 which provides this quick throw of the switch 111 is actuated to close the switch contacts when the mouthpiece is removed from its support 123. In Fig. 1 the support is shown in its horizontal position with the mouthpiece lying thereon. In this position, as said above, the switch contacts are open. Fig. 2 shows the support 123 in the position it assumes when the mouthpiece has been removed therefrom. In this position of the support the switch contacts in the motor circuit are closed and energy is supplied to the motor. Support 123 comprises a pair of spaced upwardly curved supporting arms 124 and 125. Support 124 receives the mouthpiece of the speaking tube about centrally of its length or at about the crook in the mouthpiece while the support 125 receives the flexible speaking tube at a 20 point adjacent its connection with the mouthpiece handle. Thus the speaking tube is well balanced upon the support and securely rests thereon, there being little tendency for it to be removed accidentally.
20. Support 123 further comprises an offset downwardly extending plate-like part 126 pivoted at 127 and provided with a slot 128 adapted to receive a shoulder screw 129. Screw 129 is rigidly secured to the end of the sub-base by means of inner and outer nuts 130 and 131, and this bolt provides a spacing shoulder 132 for giving the plate 126 lateral support. The movement of the support 123 is limited in its two directions by contact of the screw 129 with the ends of slot 128. The plate 126 of the support 123 is rigidly secured to a short arbor 133 (see Figs. 5 and 6) which is rigidly secured at its inner end to an arm 134 which may be made integrally therewith. This arbor 133 passes rotatably through a passage in a hollow bolt 135 which is formed at its 25 outer end with an enlarged head 136 and is threaded to receive a nut 137. The shank of the bolt 135 passes through a suitable opening in the end of the motor box and is held rigidly with respect to the motor box by means of the nut 137 and a pair of collars 138 and 139 which engage opposite sides of the said end wall of the box-like sub-base.

The outer end of the arbor 133 is bored and threaded to receive a machine screw 140 the head of which bears against the outer side of the plate portion 126 of the support 123. The said plate portion is provided with a rectangular opening adapted to fit over a squared portion 141 provided at the extreme outer end of arbor 133. Of course the said plate portion is not rotatable with respect to the arbor 133 so that the said plate portion and the arm 134 are rigidly connected to rotate together upon movement of the support 123 from its horizontal to its raised position. At its 20 upper end arm 134 is pivotally connected as at 142 (Figs. 3 and 4) with one end of a link 143, the other end of which is pivotally connected as at 144 to the upper toggle lever 113. 145 is a tension spring one end of which hooks into a perforation at 146 in the lever 143 and the other end of which hooks into a perforation 147 provided in a lug 148 extending outwardly from the periphery of washer 138. This spring acts upon the parts in such a way that the mouthpiece support tends to occupy its raised or slanting position in which position the switch contacts are closed. The strength of the spring, however, is not sufficient to resist turning movement of the levers when the mouthpiece and speaking tube are carried by the mouthpiece support.

The location of the switch operating mouthpiece support, as hereinbefore described, upon the end of the sub-base instead of its usual position above the base plate 12, makes it conveniently possible to cover all of the external working parts of the machine such as the mandrel 17 and carriage 21 with a suitable hood indicated herein by the numeral 160. It will be noted, therefore, that not only does the present invention provide a mouthpiece support and switch actuating member more conveniently located for operation, but also for providing a cover for the machine in close association with the parts covered and without awkward and ungainly portions extending beyond the base plate of the machine.

It will be seen, therefore, that the present invention provides a construction of an essentially practical nature in which the several objects are attained.

As many possible embodiments may be made of the above invention without departing from the scope thereof, it is to be understood that all matter herein set forth or shown in the accompanying drawings is to be interpreted as illustrative and not in a limiting sense.

We claim:

1. In a dictating machine, in combination, a switching lever movable from an open to a closed position against the reaction of a spring, an electric switch having a movable member, a link and lever system interposed between and operatively connecting the switching lever and said movable member, said system comprising two links one of which is connected with the other and with said movable switch member by pin and slot connections so that the same is oscillatable and longitudinally shiftable in the link and lever system, said one link also providing an angular cam surface having a high point between its angulated 65
2. In a dictating machine, in combination, a switching lever movable from an open to a closed position against the reaction of a spring, an electric switch having a movable member, a link and lever system interposed between and operatively connecting the switching lever and said movable member, said system comprising two links one of which is connected with the other and with said movable switch member by pin and slot connections so that the same is oscillatable and longitudinally shiftable in the link and lever system, said one link also providing an angular cam surface having a high point between its angulated 70
3. In a dictating machine, in combination, a switching lever movable from an open to a closed position against the reaction of a spring, an electric switch having a movable member, a link and lever system interposed between and operatively connecting the switching lever and said movable member, said system comprising two links one of which is connected with the other and with said movable switch member by pin and slot connections so that the same is oscillatable and longitudinally shiftable in the link and lever system, said one link also providing an angular cam surface having a high point between its angulated 75

sides, a roller cooperatively mounted on said other link, and a tension spring for holding said roller in contact with said cam surface.

5 2. In a dictating machine, in combination, a switching lever movable from an open to a closed position against the reaction of a spring, an electric switch having a movable member, a link and lever system interposed between and operatively connecting the switching lever and said movable member, said system comprising two links one of

10

which is slidably and oscillatably connected to be longitudinally shiftable and oscillatable in the link and lever system, a cam at an end of one of said links having a high point between adjacent surfaces, cam surface contacting means on the other of said links, and a spring for holding said contacting means against said cam.

THEODORE H. BEARD.

JOHN E. RENHOLDT.
